UNITED STATES PATENT OFFICE.

WILLIAM A. BURGER AND HENRY W. MEIER, OF LONG GROVE, IOWA.

RAIL PLATE AND CLAMP.

1,003,172.

Specification of Letters Patent. Patented Sept. 12, 1911.

Application filed January 31, 1911. Serial No. 605,823.

To all whom it may concern:

Be it known that we, WILLIAM A. BURGER and HENRY W. MEIER, citizens of the United States, residing at Long Grove, county of Scott, and State of Iowa, have invented certain new and useful Improvements in Rail Plates and Clamps, of which the following is a specification.

This invention relates to rail plates and clamps.

The present invention has for its object the provision of a rail plate and clamp having novel projections adapted to be driven into the tie to prevent displacement thereof when spiked, and, further, a new brace for the rail which, together with the plate, are formed in an improved manner to interlock with each other and with the rail, insuring the retention of the latter on the tie without displacement either on a straight track or on a curve where the lateral pressure is very great.

The present plate and clamp prevent cutting of the tie by the rail and thus prevent loosening of the spikes.

If the invention is used on a concrete or a concrete and metal tie, it can be secured by bolts instead of spikes.

The invention is fully set forth herein after and the novel features are recited in the appended claims.

In the accompanying drawings:—Figure 1 is a vertical section showing the clamp plate in use; Fig. 2, a side elevation of the abutment; Fig. 3, a view of the inner face thereof; Fig. 4, a view of the outer face thereof; Fig. 5, a top perspective of the plate; Fig. 6, a bottom perspective thereof; Fig. 7, a top perspective of a modified plate; Fig. 8, a bottom perspective thereof.

Referring first to Figs. 5 and 6, the rail plate 1 is provided on its under surface with longitudinally extending edged ribs 2 having abrupt shoulders at their ends and 45 preferably constructed and arranged as shown, the outermost ones extending for a relatively great distance and the innermost ones being shorter and separated by a considerable space at their inner ends, thus 50 increasing the number of shoulders on the ribs which engage with the wooden tie 3 and increasing the tendency of the plate to resist longitudinal displacement due to lateral pressure of the wheels of the cars, it 55 being understood that the ribs are embedded

in the tie when the plate is seated thereon. The upper face of the plate has a seat or chair 4 for the rail 5, said seat being just wide enough to receive the base of the rail, the innermost part of the plate being provided with ears or lugs 6 which are adapted to overhang the base flange of the rail, as at 7. The other margin of the seat 4 is defined by a straight shoulder 8 extending entirely across the plate 1 and of a depth substantially that of the height of the outer edge 9 of the base flange of the rail. The lower surface of the plate 1 is flat for nearly the entire length thereof so as to lie flat upon the tie 3, but its outer under part is offset or raised at 11, its upper face 12 being flat and flanked by flanges or ribs 13. Preferably square spike holes 14 are provided at opposite ends of the plate 1. To support the outer web of the rail and resist the lateral pressure, especially on curves, we provide a solid abutment or brace 15 which preferably engages the rail underneath the head and at the juncture of the web and base thereof, rounded parts 16 and 17 being provided for that purpose, the lower face 18 of the brace conforming to the top of the base of the rail, and the brace may be widened toward its outer face, as shown at 19, if desired, the angle 20 of the outer face being that best suited to give great strength to the brace. The lower part of the brace is provided with a flat base 21 of a width sufficient to fit snugly, yet easily, on the surface 12 between the flanges 13 so that the brace is prevented from twisting on its said seat. The base 21 is continued in under-projecting disposition at 22, preferably of some greater width than the base 21 and underlies the end of the plate 1, said part 22 being disposed flat against the raised surface 11 and of such thickness that it will fill the space between said surface and the top of the tie. Extending through the parts 21 and 22 of the base are spike holes 23 for the reception of spikes 24 which pass through the spike holes 14 at that end of the plate, other spikes 25 passing through spike holes 14.

Referring to Figs. 7 and 8, there is shown a plate and clamp, more particularly designed for use on straight stretches of track where no brace is employed. Here the entire upper surface 4^a of the plate is at the same level and in addition to the lugs 6, there are provided raised lugs 26 to abut 110

against the edge of the base of the rail at that point. The entire under surface 10^a of the plate is in the same plane and there are provided the ribs 2, as before, but said ribs 5 start from the outer ends of the plate.

Having thus described our invention, what we claim as new and desire to secure by Letters Patent, is:—

1. In a rail plate and clamp, the combination with a rail plate having a seat for the rail and at one end being offset or raised, of a brace or abutment for the rail which is provided with spaced connected bases receiving the raised or offset part of the plate.
- 15 2. In a rail plate and clamp, the combination with a rail plate having a seat for the rail and at one end being offset or raised, of a brace or abutment for the rail which is provided with spaced connected bases receiving the raised or offset part of the plate, 20 said brace and raised or offset part of the plate being provided with interlocking devices to prevent twisting of the abutment.
- 25 3. In a rail plate and clamp, the combination with a rail plate having a seat for the rail and at one end being offset or raised, of a brace or abutment for the rail which is provided with spaced connected bases receiving the raised or offset part of the plate, 30 said offset part of the plate being provided on its upper surface with a seat in which is

received the upper base member of the abutment.

4. In a rail plate and clamp, the combination with a plate provided with a rail seat 35 having at one side a shoulder to engage the edge of the rail base and at that end being provided with a raised or offset part whose upper surface is provided with flanges, the other side of the seat being provided with 40 lugs or ears adapted to overhang the rail base, of an abutment or brace having a part adapted to bear on the rail web and the rail base and provided with a base composed of spaced parts, the uppermost of which is 45 adapted to fit in between the flanges on the raised part of the plate and the lowermost part of said base being adapted for reception below the raised or offset part of the plate, the double base of the brace and the 50 plate being provided with openings for the reception of fastenings, and the other end of the plate being provided with openings for the reception of fastenings.

In testimony whereof, we hereunto affix 55 our signatures in presence of two witnesses.

WILLIAM A. BURGER.
HENRY W. MEIER.
